UNITED STATES PATENT OFFICE.

FLETCHER C. ROOD, OF WALLA WALLA, WASHINGTON.

FLUSHING MECHANISM FOR TOILETS.

Application filed November 5, 1919. Serial No. 337,222.

To all whom it may concern:

Be it known that I, FLETCHER C. Rood, a citizen of the United States, residing in the city of Walla Walla, county of Walla Walla, ⁵ and State of Washington, have invented certain new and useful Improvements in Flushing Mechanism for Toilets, of which the following is a specification.

My invention relates to flushing mechanisms for toilets, and more particularly to further improvements in my flushing mechanism as disclosed in my pending application, filed December 30, 1918, Serial No. 268,892.

The present invention has for its principal object to provide an improved and simplified mechanism of the character referred to which will function properly and which will permit of certain adjustments for the better regulation thereof. Other objects and ¹⁵ advantages will appear from the following description thereof, taken in connection with the accompanying sheet of drawings, in which,—

Figure 1 is a side elevation of a toilet stool ²⁰ embodying my invention;

Figure 2 is a rear view thereof;

Figure 3 is an enlarged, vertical sectional view through my improved flushing mechanism;

Figure 4 is a cross sectional view taken on line 4—4 of Fig. 3;

Figure 5 is a cross sectional view taken on line 5—5 of Fig. 3; and

Figure 6 is a vertical sectional view taken on line 6—6, Fig. 2.

Referring now more in detail to the drawings, 1 designates a stool, 2 a seat therefor, and 3 a cover for said seat. A water supply pipe 4, is connected through a valve 5, having an operating lever 6, with my improved flushing device, designated as a whole 7. The upper end of said flushing device 7 is connected by means of discharge pipe 8, with the bowl 1.

My flushing device as here shown comprises a tubular member 9, connected at its lower end to the valve 5, as indicated, and at its upper end connected with the discharge pipe 8 by means of a bushing 10, which screws into the upper end of the tubular member 9, and seats on to a flange 8^a on the discharge pipe 8. Said flange 8^a seats on a gasket 11 on an annular portion 9^a in

the tubular member 9, as clearly illustrated in Fig. 3. Mounted within said tubular member 9 is an inner tubular member 12, having at its upper end a flange 12^a, clamped between the annular portion 9^a of the tubular member 9 and the gasket 11. Thus the parts are easily disconnected for any purpose. The upper end of the inner tubular member 12 is provided with communicating holes or ports 13. The lower end of said inner tubular member 12 is provided with a slotted screw 14, having a head 15. ⁵⁵ ⁶⁰ ⁶⁵

Movably mounted within said inner tubular member 12, is a floating member 16, the top of which is provided with a short tubular member 18 therethrough, with a valve member 19 therein, held against dropping out by means of a through pin 20. Said member 19 is provided in its lower end with a head 19^a, adapted when said head 19^a is raised to close the small tubular member 18. ⁷⁰ ⁷⁵

A hinge rod 21 is provided through the hinge members 22, 22, of said seat 2 and cover 3, said rod being provided with a crank arm 23, connected by means of a connecting rod 24 with the valve lever 6. A coiled spring 25 is mounted on said rod, one end of which spring is secured to the cover hinge, and the other end is secured to said lever 23. Said rod 21 is also provided with a lug 21^a, adapted to be normally held in engagement with a similar lug 26 on the hinge member 22 by said spring 25. Said flushing mechanism is automatically operated by the lowering of said cover 3, as indicated in Fig. 1, the valve lever 6 being raised to open the valve 5. With the cover 3 in raised position, the valve lever 6 would be down, as would be the crank arm 23 and rod 24, and the hand lever would be raised. Said hand lever 27 can be moved forwardly at will, while the cover 3 is raised, so as to flush the toilet while a person is seated if desired. ⁸⁰ ⁸⁵ ⁹⁰ ⁹⁵

I will now describe the use and operation of my device.

The water supply is through the pipe 4, the flushing device 7 and the discharge pipe 8. The water is controlled by the valve 5, and the floating valve member 16, seating against the gasket 11 at the upper end of the inner tubular member 12. When the valve 5 is open, water flows up through tubular member 9, through the openings 13, and out ¹⁰⁰ ¹⁰⁵

through the discharge pipe 8 to the bowl. An upward current of water is also created in the inner tubular member 12, the water passing through the slotted screw 14, causing the floating member 16 to rise until it finally seats against the gasket 11, where it is held by the force of the water, thus cutting off the flow of water through the openings 13 and through the discharge pipe 8.

10 The force of the water also closes the valve 19^a of the floating member 16 and holds it closed until the main valve 5 is closed. When valve 5 is closed, the valve 19^a will open by gravity and break the water seal 15 which might continue to hold the floating member 16 against the gasket 11, closing the discharge pipe 8. As soon as the valve 19^a opens, the member 16 can and will settle by gravity to the bottom of the chamber in 20 tubular member 12, ready to be again operated when the valve 5 is again opened.

The quantity of water going through the mechanism at a single operation depends upon how rapidly water is permitted to flow 25 into the lower end of the inner tubular member. This can be regulated by adjustment of the slotted screw 15. The more rapidly water is admitted to said member 12, the more quickly the floating valve 16 is raised 30 and seats against the gasket 11 and the less the quantity of water passing through the device to the bowl. The more slowly water enters the inner tubular member 12, the longer it takes for the floating valve member 16 to rise and cut off the flow of the water through the discharge pipe 8, and the greater the quantity of water passing 35 through the device to the bowl.

The two valves 5 and 16 are never closed 40 at the same time excepting for the brief period required for the breaking of the water seal, immediately after closing valve 5. They are never both open at the same time excepting while the flushing operation 45 is taking place.

I am aware that changes can be made in the details of my invention as here shown and described, and I do not, therefore, limit the invention to the details here shown, except as I may be limited by the hereto appended claims.

I claim:

1. In a device of the character referred to, in combination, a tubular member, a valve 55 controlling the inflow of water to the lower end thereof, an inner tubular member providing an annular space between said members, means for attaching an outlet pipe to the upper end of said inner tubular member, said inner member having inlet openings through its wall at the upper end thereof, and having an inlet at its lower end, a valve member in said inner tubular member adapted 60 to be bodily raised to the upper end thereof by inflowing water, said valve mem-

ber being adapted to close the openings through the side of said inner member when it reaches the upper end thereof, and a valve-controlled passageway through said valve member adapted to permit water to 70 pass through said passageway after said valve member has reached its upward limit.

2. In a device of the character illustrated comprising in combination an outer tubular member, a valve controlled supply opening 75 at its lower end, an inner tubular member of less size in the upper part of said outer tubular member, an outlet pipe connected with the upper end of said inner tubular member, said inner member having inlet 80 openings through its side, near its upper end, and having an inlet opening at its lower end with means for regulating the size thereof, a cylindrical valve member in said inner member adapted to be raised to the upper end thereof by inflowing water and to close the inlet openings through the side thereof, a passageway through said valve member, and a pin fitted loosely through said passageway and having a head to close the under end of said passageway. 85

3. In a device of the character referred to comprising in combination, a tubular body member, a valve controlled supply inlet at one end of said body member, a second tubular member communicating with the first body member through its side near one end and also communicating with said first body member at its other end, means for connecting an outlet pipe to said second tubular member, a movable valve member in 95 said second tubular member adapted to be bodily raised to the upper end thereof by inflowing water into said second tubular member, said valve member being adapted to cover and close the communicating opening through the side of said tubular member, whereby to close communication between said tubular members through said side opening, and means forming a part of said movable valve member adapted to provide a passageway therethrough and having a movable part to open and close said passageway, whereby to permit said valve member to settle by gravity after closing the communication between said tubular members through the side of said second tubular member, substantially as described. 100

4. In a device of the character described, in combination, an outer cylindrical member, a valve for controlling inlet to the lower end thereof, means for opening said valve manually, an inner cylindrical member of less diameter at the upper end of said outer member, said inner member having a communicating inlet through its side, near its upper end, communicating with the outer member, and having its lower end closed and provided with a small inlet opening, with 110 means for regulating the size thereof, a valve 115

member movable bodily within said inner cylindrical member by inflowing water and adapted to close said inlet opening through the side of said inner member when moved to the upper end thereof, and a valve controlled passageway through the body of said valve member, substantially as and for the purpose indicated.

Signed at Walla Walla, county of Walla Walla, and State of Washington, this 11th ¹⁰ day of October, 1919.

FLETCHER C. ROOD.

In presence of:

W. R. PAXTON,
W. G. HUGHES.
